PUMPING APPARATUS

William H. Sloan, Washington, D. C., assignor of
one-half to M. F. McCann, Seale, Ala.

Application July 24, 1936, Serial No. 92,419

11 Claims. (Cl. 103—72)

This invention relates to improvements in pumping apparatus and in particular to that type which is conventionally known as a rope or chain pump, designed for elevating liquids.

At the present time, liquids are raised from wells such, for example, as water or oil wells by means of pumps which involve tubing, pistons, cylinders, valves and other mechanical devices, all subject to wear, corrosion, leakage, and mechanical difficulties, giving rise to inefficiency, relatively great expense in installation, maintenance, and power required for operation, and the greater the distance of elevation of the liquid, the larger these factors enter into the problems of use of such apparatus.

The primary purpose of my invention is to overcome the problems found in the known pumping apparatuses above referred to by the provision of a simple, inexpensive and highly efficient apparatus, greatly enlarging the field of usefulness, while eliminating numerous and complicated mechanical parts, and at the same time effecting a saving of power, time and labor, to say nothing of the saving of expense in manufacture.

To this end, my invention takes advantage of the principle that when a flexible cable, such as rope, chain or the like, is passed through a body of liquid, a definite amount of the latter will adhere to the surface of the cable depending primarily upon the size and speed of operation of the same, and that by a sudden change in the direction of travel of the cable the entrained liquid may be displaced therefrom.

I am aware that broadly speaking it has been heretofore proposed to convey liquids to higher elevations by cable means and the present invention represents improvements over these prior constructions by means of which improvements the apparatus is made more practical and efficient, universally adaptable for many purposes, and operable with much less power requirement.

With the foregoing in view, one of the objects of the invention is the provision of a special mounting for the cable means, enabling the application or removal of said means without disassembling the parts for such purpose, said mounting being so constructed and arranged as to maintain the cable reaches at all times in proper relative position for effective operation.

Another object in view is the provision of means in association with the cable conveying means for controlling the feed of liquid to said conveying means in such a manner as to prevent the retarding effect incident to the move-

ment of said means downwardly into the liquid preliminary to the upward movement of the cable means for conveying the same in the upward direction, which effect is found to occur in the apparatus heretofore proposed.

A further object of importance of my invention is the provision of means for producing high pressure flow of the elevated liquid through the instrumentality of an associated impeller structure.

Other and further objects and advantages of the invention will be hereinafter set forth and the novel features thereof defined by the appended claims.

In the drawings:

Fig. 1 is a vertical sectional view taken about 15 on the plane indicated by the line 1—1 of Fig. 2 through an apparatus constructed and arranged in accordance with my invention;

Fig. 2 is a similar view taken about on the plane of the line 2—2 of Fig. 1;

Fig. 3 is a fragmentary sectional view of a modified form of my invention and more specifically disclosing the impeller device associated with the cable conveying members;

Fig. 4 is a vertical, sectional view on the line 25 4—4 of Fig. 3;

Fig. 5 is a vertical, sectional view of the lower portion of the pumping structure including the encasing device for controlling the feed of liquid to the cable to be elevated by the cable members; 30

Fig. 6 is a vertical, sectional view on the line 6—6 of Fig. 5 looking in the direction of the mouth or feed opening of the casing member; and

Fig. 7 is a fragmentary detail view of another mounting for the upper pulley member enabling 35 the removal of the cable without dismounting the pulley.

Like reference characters designate corresponding parts in the several figures of the drawings.

Referring to the drawings and particularly to that form of the apparatus which is shown in Figs. 1 and 2, 1 designates a suitable framework or housing support which is mounted upon the base 2 over the body of liquid to be pumped or elevated. This structure includes a removable top or cover section 3 within which is mounted the pulley shaft 4, preferably of non-corrosive material such as stainless steel or the like. The end portions of the shaft are removably mounted 50 in the bearing brackets or plates 5, one such plate being secured by fastenings 6 to the inner wall of the support 1 at each side thereof as clearly shown in Fig. 1. The ends of the shaft 4 project from the frame support 1 and to one of said 55

ends is connected a suitable motor 7 as by means of the shaft coupling 8 for use when the device is to be power driven, said motor being mounted upon a convenient bracket 7' attached to the 5 side of the support 1.

The other end of the shaft is provided with a belt pulley 9 over which the belt 10 passes for driving the shaft manually, as by means of the crank handle 11, fastened to the driving pulley 10 12 for the belt. It is to be understood that either of these driving means may be dispensed with, depending upon the available source of power, and I do not wish to be restricted to the use of either for the purposes of this disclosure.

15 Upon the shaft 4 within the top of the frame 1 is fixedly secured a pulley 13, which in this form of the apparatus is double grooved so as to accommodate two cable members or ropes 14 of the endless type and of sufficient length to extend downwardly through an opening in the base 2 into the body of liquid which is to be elevated. In this connection it is to be observed that I prefer to employ a pulley member made of some material which will not be affected, chemically 20 or otherwise, by the liquid to be pumped, such as for example "micarta", non-corrodible metal, or the like. As for the cables, these are preferably of cotton rope suitably treated by waterproofing material or rubber coated to protect the same 25 against deterioration over long periods of time.

30 At the lower end of the cable means a pulley device is provided over which the cables are trained. This device consists of a slideable frame 15 provided at its opposite ends with guide supports to receive the vertical guide rods 16 which depend into the liquid from the upper casing structure 1 to which they are connected by suitable fastening means 17. It will be observed in Fig. 1 that one side of the frame 15 is open and 35 formed with a depending arm 18 to receive one end of the pulley shaft 19 which is journaled in the opposite side of the frame at its other end. On this shaft the pulley member 20 is secured, said pulley conforming to the pulley 13 on the upper shaft 4. It will be apparent that the 40 weight of the pulley device just referred to tends to maintain the cable members taut and through the instrumentality of the guide means, these cable members are prevented from twisting or 45 becoming entangled in the use of the device.

50 The free mounting of the frame member 15 upon the guide rods enables the cables to stretch or contract in the use of the same for the purposes of this invention and it will be apparent that when it is desired to remove the cables from the frame 15, this may readily be accomplished by pulling the frame to the top of the well, if it be in a well, adjacent the platform or base, whereupon the cable or cables may be 55 slipped over the arm 18 for displacement. In the same manner the application of the cables to the frame and its pulleys is readily accomplished by the reverse of the operation.

60 Likewise the displacement or disposition of the cables from or upon the pulley member 13 on the shaft 4 may be accomplished by simply lifting the top structure or cover which frees the shaft for displacement from the bearings in the plates 5. Obviously, the foregoing operations do 65 not require removal of bolts or dismantling of the parts to any great extent and a considerable saving in time is effected by this arrangement.

70 Passing now to the structure of the cover section 3, it will be observed particularly in Fig. 2 75 that the same is formed with oppositely dis-

posed outlet passages 21, the inner wall of each of which extends to a point quite close to the face of the cable members so as to assist in the displacement of the liquid from the ropes in a manner to be further described hereinafter. 5

As a feature of convenience, the top member is provided with a drinking fountain attachment, said attachment being composed of the basin or cup 22 through the bottom of which extends a tubular member 23, the said tubular member being closed at the bottom and provided with an opening 24 at one side so as to act in the nature of a scoop to receive water which may be caught by the tube and caused to rise through and flow over the upper extension 23'. This drinking 10 fountain device is rotatably supported upon the upper cover section so that the mouth or entrance of the tube 23 may be turned into opposite scooping positions or at right angles to such positions when it is not desired to operate the drinking 15 fountain.

The operation of this device will be apparent from the foregoing description.

If it is desired to drive the conveying means by power, the switch 7a of the electric motor 7 25 is closed whereupon the cable members 14 will be rapidly revolved around the pulley devices and in the direction of the arrows as shown in Fig. 2. This action will cause the cable members to pick up a film of water or other liquid through which 30 the cable means passes and convey said liquid to the top of the apparatus. The water obviously clings to the up moving reaches of the cable means until said cable means changes its direction of travel over the upper pulley members, 35 which sudden change displaces the liquid which is thrown against the side of the delivery spout 21 to flow therethrough as indicated by the arrows in Fig. 2. It will be understood that the pumping means or cables may be reversely 40 driven, in which case the liquid would be flowed out of the opposite spout 21. In either direction of flow the fountain attachment 22 may be properly turned to position for flowing the liquid out of the tube extension 23', for drinking purposes 45 or otherwise.

I have found from experimentation that a pump of this type may be employed where the standard form of cylinder pump cannot operate, or will operate at a disadvantage due to wear 50 from sand and other foreign matter in the liquid to be pumped. Such a pump construction as disclosed does not require priming, and where it is motor driven, the starting load imposed upon the motor is very low. In fact by the time the liquid 55 is entrained to the full length of the up running reach or reaches, the motor has had opportunity to reach its full speed. This is a distinct advantage over known motor driven pumps where the starting load is very hard on the motor and requires, for this reason, a greater horsepower to take care of the starting load and the frictional losses in the pump and the riser tube. With the type of pump herein described, all valve parts are 60 dispensed with and the difficulties of freezing 65 which are experienced with the usual type of pump are entirely overcome.

As regards the capacity of such a pump, I have found by experimentation that this is controlled directly in proportion to the size of the cables and 70 the number of the same, regardless of the lift or elevation to which the liquid is raised. For a given size of cable, twice as much liquid will be elevated if two cables are employed, and four times as much if four cables are employed. In 75

view of the elimination of valve actions and reciprocating instrumentalities, the noise of such mechanisms is also entirely eliminated by this construction of pump.

5. Where it is desired to increase the efficiency of the pumping operation and particularly where high pressure is desirable, the pumping apparatus just referred to may be modified by the incorporation of an impeller device in its construction. 10
10 Such an arrangement is illustrated in Figs. 3 and 4 where the upper cable pulley 25 is enclosed within a housing 26. This housing is secured to the sides of the support 1 by means of the fastening members 27 and said housing is formed at 15 its central portion with an annular extension 28 to accommodate the impeller 29 secured to or forming a part of the pulley device 25.

In this form of the device I have shown the pulley as provided with four grooves to receive 20 four cable members, by means of which a sufficient quantity of liquid may be raised as described hereinbefore into the casing 26. This liquid will be thrown into the peripheral portion or extension 28 where the said liquid will be subjected to 25 the impeller action and thrown with great force from the outlet 30, from whence it may be conveyed to suitable reservoirs at an elevation.

This form of construction may be employed for spraying or other similar purposes, in which 30 event the necessary flexible conduits would be connected to the outlet 30 of the casing 26.

A still further modification of the apparatus above described may be resorted to preferably for the purpose of increasing the efficiency and capacity of the pumping device. Such modification is shown in Figs. 5 and 6 of the drawings. It will be apparent that in the form of the device illustrated in Figs. 1 and 2 the down moving reach of the cable or cables will tend to pick up the liquid 40 and convey it downwardly through that portion of the reach which extends into the body of the liquid. This necessarily produces a retarding action and in order to take care of this factor, greater power is required than would be the case if 45 the liquid were excluded from the down moving reach of the cable.

By placing the casing 31 around the portion of the cable means and pulley device which is below the liquid level and providing such casing with an opening 32 which is of an area calibrated to take care of the amount of liquid which is capable of being conveyed by the cable means, this difficulty is overcome. The housing is provided with a partition member 33, the lower wall of which is bent laterally as indicated at 34 adjacent the pulley member so as to act to prevent the liquid entering the casing from following the pulley in the rotation thereof. In this construction, the liquid is prevented from contacting with the down moving reaches of the cable means.

As fast as the liquid flows into the opening 32, the cable means acts to pick up the liquid and to convey it in a relatively thin film upwardly to the top of the pumping apparatus. The opening 32 obviously would be changed according to the nature of liquid which is to be elevated so as to adequately control the feed of the liquid into the casing 31 only in proportion to the amount which can be handled by the cable means.

70 In Fig. 7 I have shown a slightly modified form of pulley mounting wherein the motor 1 is directly connected to the pulley shaft 4a which has a bearing at only one side of the support 1. This shaft extends part way across the support and 75 has mounted upon its end the pulley member 13a

to accommodate the various endless cables for conveying the liquid. Whenever it is necessary to displace any one or all of these cable members, it is only necessary to slip the same off of the free end of the pulley in a manner described with reference to the displacement of the cables from the pulley frame 15. This eliminates any necessity for dismounting the mechanism for the purpose of repair or replacement of cable members.

It is to be understood that pumping apparatus of the type disclosed herein is capable of many uses or applications. Among these used may be mentioned that of raising water from open wells, pumping bilge water from boats, removing water from cellar drains or excavations, conveying water in large quantities to higher elevations for irrigation purposes, handling such liquids as are manufactured in distilleries, pumping oil from oil wells, acids, alkalies or the like.

In this connection, the apparatus may be made 20 in different sizes and with varying numbers of cable members according to the capacity or requirements of the particular use. For this reason, it is to be understood that I do not wish to be restricted in respect to the field of application of the pump device which forms the basis of this disclosure.

Having thus described my invention, what I claim as new and desire to secure by Letters Patent is:

1. Pumping apparatus of the type described comprising a supporting frame, a pulley member mounted thereon, endless cable means mounted on said pulley member, a second pulley member cooperating with the cable means and sustained 35 thereby in the liquid to be pumped, a frame for said second pulley, guide means extending from the supporting frame into the liquid to be pumped and with which the second pulley frame is slidably connected for maintaining the operative relation of said cable means with respect to the first mentioned pulley member and permitting said second pulley to be raised to the supporting frame for access, and means for moving the cable means about said pulley members, said guide means 45 comprising a rod and said second pulley frame being provided with means interlocking said rod.

2. Pumping apparatus of the class described, comprising a supporting frame, a pulley shaft mounted on said frame and a pulley member fixed 50 on said shaft, endless cable means extending about said pulley member, a second pulley member co-acting with the cable means below said first pulley member for holding the cable means tensioned, a frame in which the second pulley member is mounted and having an open side, said endless cable means being removable laterally from the pulley members through said open side without dismounting the same, and means for actuating said cable means about said pulley 55 members.

3. Pumping apparatus of the class described for raising liquids, comprising a support, a pulley member mounted thereon, an endless cable mounted on said pulley member and extending 65 downwardly into the liquid to be raised, means surrounding that part of both reaches of the cable projecting into the liquid and having an opening arranged between the down and up reaches of the cable for controlling the feed of 70 the liquid to be raised to the up reach of the cable and means for driving said cable from said pulley member.

4. Pumping apparatus of the class described for raising liquids, comprising a support, a pulley 75

- member mounted thereon, an endless cable mounted on said pulley member and extending downwardly into the liquid to be raised, means surrounding that part of the cable projecting into the liquid for controlling the feed of the liquid to be raised to the up reach of the cable, guide means for said surrounding means preventing twisting of the cable, and means for driving said cable from said pulley member, said means surrounding the cable consisting of a casing for excluding the liquid from the up and down moving reaches of the cable and having a feed opening into which the liquid flows to the up moving reach of said cable.
15. Pumping apparatus of the class described for raising liquids, comprising a support, a pulley member mounted thereon, an endless cable mounted on said pulley member and extending downwardly into the liquid to be raised, a second pulley member sustained by the downwardly extending portion of the cable for tensioning the same, including an open sided frame for said pulley member, said frame comprising a housing for enclosing the up and down moving reach of the cable below the liquid level and having a feed opening to admit the liquid to the up moving reach thereof, means for actuating the cable by one of said pulley members, and guide means to which said second pulley member and frame is slidably connected and interlocked against rotary movement.
6. Pumping apparatus of the class described for raising liquids, comprising a support, a pulley member mounted thereon, an endless cable mounted on said pulley member and extending downwardly into the liquid to be raised, impeller means associated with said pulley member and of greater diameter than said member for imparting pressure to the liquid raised by the cable means, and means for actuating said cable through said pulley member.
7. Pumping apparatus of the class described for raising liquids, comprising a support, a pulley member mounted thereon, an endless cable mounted on said pulley member and extending downwardly into the liquid to be raised, impeller means associated with said pulley member for imparting pressure to the liquid raised by the cable means, an impeller housing surrounding the pulley member into which the liquid is conveyed by the cable means, and common means for actuating said pulley and impeller means.
8. In apparatus of the class described for elevating liquids, comprising a supporting frame, a pulley member mounted at the top of said supporting frame, cable means engaging said pulley member and depending into the liquid to be raised, means for yieldably holding the cable means in the said liquid, a cover member for the top of the supporting frame including a discharge passage for the liquid, and water discharge means mounted on said cover member and having means extending below said cover member to receive the liquid as it is raised by the cable means over the pulley member and convey it from the supporting frame.
9. In apparatus of the class described for elevating liquids, comprising a supporting frame, a pulley member mounted at the top of said supporting frame, cable means engaging said pulley member and depending into the liquid to be raised, means for yieldably holding the cable means in the said liquid, a cover member for the top of the supporting frame including a discharge passage for the liquid, and water discharge means mounted on said cover member and having means extending below said cover member to receive the liquid as it is raised by the cable means over the pulley member and convey it from the supporting frame, said water discharge means being adjustable to control the intake and discharge of the liquid to and from the same.
10. Pumping apparatus of the class described comprising a supporting frame, a pulley member mounted on said frame, a plurality of endless cable members engaging said pulley member and depending into the liquid to be raised, an impeller member comprising a disc of greater diameter than the pulley member and mounted between the cable members, and a casing surrounding said impeller member into which liquid elevated by the cable members is introduced by said cable members, and means for operating the pulley and impeller member to create pressure for ejecting the liquid from the impeller casing.
11. Pumping apparatus of the class described for raising liquids comprising a support, a pulley member mounted thereon, an endless member mounted on said pulley member and extending downwardly into the liquid to be raised, a casing on said support to receive the liquid raised, means in said casing for imparting pressure to the liquid, and means for actuating said pulley member and pressure producing means.

WILLIAM H. SLOAN.
